UNITED STATES PATENT OFFICE.

JEROME F. BUSEY, OF VENICE, PENNSYLVANIA.

LINK-MACHINE.

SPECIFICATION forming part of Letters Patent No. 329,010, dated October 27, 1885.

Application filed August 3, 1885. Serial No. 173,309. (No model.)

To all whom it may concern:

Be it known that I, JEROME F. BUSEY, of Venice, in the county of Washington and State of Pennsylvania, have invented a new and useful Improvement in Link-Machines; and I do hereby declare the following to be a full, clear, and exact description thereof, reference being had to the accompanying drawings, forming a part of this specification, in which—

10 Figure 1 is a vertical longitudinal section on the line xx of Fig. 2. Fig. 2 is an end view of the machine shown in Fig. 1, looking in the direction of the arrow a . Fig. 3 is a vertical cross-section on the line $x'x'$ of Fig. 1. Fig. 4 is a perspective view of parts. Fig. 15 5 is an enlarged vertical cross-section of the shaft 9, showing the face of the pinion 8 and the jogs which are affixed thereto. The teeth on the periphery of this pinion are not shown, 20 the regular circular line inclosing the shaft 9 indicating the pitch-line thereof.

Like letters and figures of reference indicate like parts in each.

In the drawings, 2 represents the bed-plate 25 of the machine. It supports two vertical standards, 3 and 4, in which is journaled a horizontal rotary shaft, 5, to the rear end of which is fixed a belt-pulley, 6, and to an intermediate point between the standards is 30 keyed a spur-wheel, 7. The shaft 5 is the main driving-shaft of the machine, and is continuously rotary. Power is imparted to it by the belt-pulley 6. The spur-wheel 7 meshes with a gear-wheel, 8, which is loosely 35 journaled on a fixed horizontal shaft, 9, and the wheel 8 drives a vertical spur-wheel, 10, which is shown in Fig. 3 in full lines, and by dotted lines in Fig. 2, but is not shown in Fig. 1. The shaft 11 of the latter wheel is journaled horizontally in suitable bearings, and extends to the front of the machine, where a cam, 12, is affixed to it. The gear-wheels 7 and 8 and the cam 12 are continuously moving. The mandrel 13, which bends the chain-links, 45 consists of a pear-shaped bar or shaft set axially within a fixed hollow cylindrical worm-block, 14, so as to be rotatory therein. The rear end of the mandrel-shaft is squared, and projects back of the worm-block into a squared 50 socket in the end of a rotatory drum or shaft, 15, on which are arranged vertical collars 16,

bearing against the side of a vertical housing, 17, and the end of the worm-block, respectively. These collars steady the drum and the mandrel in their rotation. On a shaft, 15^a, 55 which is affixed to the rear end of the drum 15, and is practically a continuation thereof, is keyed a spur-wheel, 18, which meshes into a loose spur-wheel, 19, on the shaft 9. The spur-wheel 19 has twice as many teeth as its driven wheel 18, and the shaft of the latter is journaled in the housings 17. The inner surface of the worm-block 14 around the mandrel is helically grooved, and at the rear end thereof a hole or passage, 21, extends transversely through the worm-block, and through the box or casing 22 which incloses it, Figs. 1 and 3. A side of the mandrel 13 is longitudinally slotted or grooved throughout its whole length, as at 23.

In operation the end of a heated bar of proper diameter is inserted through the hole 21 into the slot 23, which is then opposite thereto, and as the mandrel rotates it will bend this inserted end into a hook and will 70 commence to wrap the bar round its surface. During this wrapping the helical groove in the worm-block will engage the heated bar, and will guide it so that it will emerge from the front end of the block in the form of a helix, as will be readily understood. After each rotation of the mandrel, producing a single coil of the helix, laterally-moving forming-dies 25 and 26 are moved against the projecting circular coil and bend it into an elliptical form, the proper shape for a chain-blank, 85 and a reciprocating knife descends and cuts off the blank.

I will now describe the operation of these parts.

The forming-die 25 is mounted in horizontal ways or slides 27 at the front of the machine, and is driven by a cam, 28, which rotates within a heart-shaped cam-space, 29, made in the body of the die, and so formed 95 that after the cam has moved the die to its farthest position the end of the cam, in its further movement, (see Fig. 2,) will suddenly release its hold on the die and allow it to be retracted by a spring, 30, one end of which 100 bears against a part of the die and the other end against a tongue or stop, 31, on the frame

of the machine. The cam 28 is driven by and keyed to a shaft, 32, on which is fixed a spur-wheel, 33, Fig. 3. The latter spur-wheel gears with and is driven by the pinion 18, which is of equal diameter with the spur-wheel 33, is keyed to the mandrel-shaft 15¹, and is driven by the spur-wheel 19, as before described. The mandrel and the cam 28 therefore rotate synchronously and perform the same number 10 of revolutions in a given time. Suppose the mandrel and cam be started from the positions which they occupy in Fig. 2, and suppose that the knife 24 has just severed a blank from the coil, the first effect of the cam's motion is to 15 release the die and to allow the spring 30 to draw it suddenly back. The cam-space 29 is so shaped that the cam will not begin to advance the die until the mandrel has performed about three-quarters of its revolution, and 20 until about three-quarters of the link-blank has emerged from the worm. Then the advance of the die will cause its front end, which is made concave, to engage the side of the projecting coil and to bend it inward, 25 at the same time guiding the coil as it continues to emerge from the worm. The cam will have moved the die to its farthest point at the same time that the mandrel has completed its revolution and formed a single blank. 30 By automatic mechanism, which I will herein-after describe, the die and mandrel then come immediately to rest and occupy the relative positions shown in Fig. 2. During this period of rest the die 26, which is mounted in slides on 35 the other side of the mandrel, advances, bends its adjacent side of the projecting coil toward the mandrel, and then recedes. The knife 24 then descends and, engaging the coil as it comes from the worm, cuts off the blank 40 against a fixed bed-knife, 34. After this the knife is retracted and the cam 28 and the mandrel begin to act, as before explained. The effect of the forming-dies is that when the blanks are severed they will have been shaped 45 into the proper elliptical form of a chain-link, instead of the circular form in which they are usually turned out from link-machines. The cam 12, which moves the die 26, is continuously rotary and works within a yoke-space, 50 35, of such shape relatively to the yoke-space of the other cam, 28, that the die 26 will not be moved against the link-blank until immediately after the die 25 has been moved to the position shown in Fig. 2, and the mandrel has 55 performed its complete revolution. The die 26 has a concave face similar to that of the die 25, and is retracted by a similar spring, 30. Instead of the coiled springs 30, leaf-springs 60 or any other equivalent mechanism may be used to retract the shaping-dies. In Fig. 2 I have shown the coiled springs 30, and in addition, and as auxiliary thereto, I have shown leaf-springs 30^a, which are fixed to a stationary part of the machine-frame and bear upon 65 pins on the faces of their respective dies. The leaf-springs exert a force upon the dies in the

same direction and for the same purpose as their companion springs 30.

Owing to the helical form of the link-blank, which emerges from the worm at a point nearer 70 to the base of the mandrel, the face of the die 25 should be made thicker than that of the die 26, so that they may engage the blank properly. The reason why the die 26 is not advanced until the link-blank has been formed 75 by the mandrel and worm is that I thus avoid the buckling against the face of the die, which might otherwise occur. As before stated, the cam 12 is driven by the engagement of the spur-wheels 10 and 8, which are of equal diameter and revolve without intermission.

The gearing which imparts intermittent motion to the cam 28 and to the mandrel is thus constructed: A lateral cam, 36, is fixed to the stationary shaft 9, the side of the pinion 85 19 being recessed at 39 around its axis, so that it may fit against the back of the cam and rotate over it. A corresponding cam, 37, is fixed to the adjacent side of the spur-wheel 8, and the latter is made movable lengthwise 90 on its shaft and given a tendency toward the wheel 19 by means of a coiled spring, 38, which is interposed between the wheel 8 and the vertical standard 4. As the spur-wheel 8 rotates on its axis, its cam 37 will engage the fixed cam 95 36, and the wheel will be forced thereby away from the pinion 19 against the tension of the spring 38, and as soon as the cams have passed each other the spring will throw the wheel 8 forward again against the face of the pinion, 100 the cam 37 then entering the annular recess 39. The face of the spur-wheel 8 next the wheel 19 is provided with two lateral jogs or lugs, 40, each of which extends concentrically with the shaft 9, preferably for a length of 105 about forty-five degrees, the ends of the jogs being, respectively, diametrically opposite to each other. The face of the pinion 19 next the spur-wheel 8 has similarly-arranged jogs 41 41^a. 110

When the cam 36 is engaged with the cam 37, it will push the wheel 8 away from the pinion 18, so as to separate the jogs, as shown in Fig. 1. If, now, the parts are as shown in that figure, with the wheel 8 revolving in the 115 direction of the arrow of motion, b, as soon as the cam 37 has passed the fixed cam 36 the spring 38 will force the spur-wheel 8 toward the pinion 19, and will bring the faces of the jogs on both wheels in contact. The pinion 8 120 and its jogs will thus revolve until the back ends of the jogs 40 have passed the front ends of the jogs on the then still pinion 19, when the wheel 8 will be thrown farther forward, so as to bring the jogs of each respectively in 125 contact with the side of the opposite wheel. When, however, the front ends of the jogs 40 reach the rear ends of the jogs 41 41^a, they will engage or lock, and the rotation of the driving-wheel 8 will turn the wheel 19 until the cams 130 36 and 37 come into contact, when the driving-wheel 8 will be pushed back on its shaft far

enough to disengage the jogs. The effect of this is to stop the wheel 19 and its driven parts. The wheel 8 then revolves freely until the cams have passed, and until the front and rear ends of the jogs 40 and 41^a again engage, when the wheel 19 receives another intermittent motion, and so the operation is continued. As before stated, the ends of the jogs on the several wheels are diametrically opposite to each other. The wheel 8 will therefore impart a semi-revolution to the wheel 19 during its every whole revolution, and will cause it to remain at rest during the remainder thereof. Of course the teeth of the pinion 7 should be made wide enough to permit the wheel 8 to be moved lengthwise on its shaft without throwing it out of gear. A suitable cam or other equivalent moving device may be substituted for the spring 38. The cam 12, which is driven by the continuous rotation of the spur-wheel 8, is so timed with the cam 28 that it does not advance its die until the cam 28 and the mandrel have been stopped by the intermittent gearing just described, and the cam 28 and the mandrel, though moving during only one-half of the time of motion of the cam 12, are caused to perform whole revolutions in the same period of time by making the pinion 18 of one-half the diameter of its driving-wheel 19. The former will therefore turn completely around during the semi-revolution of the wheel 19 and the full revolution of the wheel 8.

The operation of the knife 24 is yet to be described. It is set vertically above the bed-knife 34, and above the exit of the worm, and is affixed to a head, 42, which reciprocates within a box or casing, 43. A vertical slot is made in the knife-head, and in it is set a helical spring, 45, which bears against the knife-head at the top of the slot, and upon a cross bar or brace, 44, affixed to the casing 43, thus exerting an upward pressure on the head. The latter projects above the casing 43, and bears against the periphery of an abrupt cam, 46, which is affixed to the main driving-shaft 5 and is rotatory therewith. Once in each revolution of the shaft the cam forces the knife downward against the pressure of the spring 45 and severs the link-blank, and then the cam 50 immediately releases the knife-head and suffers the spring to move it up in the casing and to withdraw the knife 24. The knife-cam is timed relatively to the cam 12 and to the mandrel, so that it only actuates the knife after the blank has been wormed out, and after the die 26 has shaped it.

Thus constructed, the machine is very valuable on account of its simplicity and efficiency of action. The shaping-dies 25 and 26 are of particular importance, because they enable the machine not only to make an annular link-blank, but also to form it into the proper elliptical shape, thereby avoiding the necessity of reheating and shaping the blank by a subsequent process after it has been taken from the link-machine.

Of course the shaping-dies are so formed as not to approach far enough to close the ends of the links entirely. They leave a sufficient space between them to permit the insertion of other links when the chain is finally welded.

If desired, one of the dies 25 or 26 may be fixed and the other movable toward it, though this would be disadvantageous on many accounts.

I do not desire to limit myself closely to the precise arrangement of mechanism herein shown and described; but

What I claim as my invention, and desire to secure by Letters Patent, is—

1. In a link-machine, the combination of a rotatory mandrel for forming the link-blank into a helical configuration, shaping-dies situated at the exit of the mandrel, arranged to clamp the blank and to compress it into proper shape, and mechanism for actuating the dies, substantially as and for the purposes described.

2. The combination, in a link-machine, of a rotary mandrel for forming the link-blank into a helical configuration, shaping-dies situated at the exit of the mandrel, and movable toward each other to clamp the blank and to compress it into proper shape, and mechanism for actuating the dies, one of the latter being so actuated as to move toward the blank during the process of forming the blank by the mandrel, and the other die actuated so as to be thus moved after the formation thereof, substantially as and for the purposes described.

3. In a link-machine, the combination of a rotatory mandrel for forming the link-blank into a helical configuration, shaping-dies situated at the exit of the mandrel, arranged to clamp the blank and to compress it into proper shape, mechanism for actuating the dies, and a spring for retracting the dies, substantially as and for the purposes described.

4. The combination of a mandrel for forming the link-blank into a helical configuration, reciprocally-moving clamping-dies situated at the exit of the blank from the mandrel, and cams for actuating the dies, said cams operating within yokes in the heads or frames of the dies, substantially as and for the purposes described.

5. In a link-machine, the combination of a rotatory mandrel for forming the link-blank into a helical configuration, shaping-dies situated at the exit of the mandrel, arranged to clamp the blank and to compress it into proper shape, mechanism for actuating the dies, and a knife actuated so as to sever the blank after it has been shaped by the dies, substantially as and for the purposes described.

6. The combination of a link-forming mandrel, 13, and a shaft for rotating the same, a shaping-die, 26, and a shaft for actuating it continuously, a gear-wheel, 8, movable lengthwise on its shaft, connected with the continuously-moving shaft of the said die, and pro-

vided with a lateral cam, 37, a gear-wheel, 19, mounted on the shaft of the wheel 8, and actuating the shaft of the mandrel, these gear-wheels being provided with lateral jogs, a lateral cam capable of engagement with the cam 37, and of separating the gear-wheels, and devices for causing them to approach when freed from the cams, substantially as and for the purposes described.

10 7. The combination of a shaft, 9, a gear-wheel mounted on the shaft and capable of motion lengthwise thereon, a second gear wheel, 19, one of the gear-wheels being provided with a lateral cam, 37, a second cam for 15 engaging the cam 37 and separating the said

gear-wheels, and devices for causing them to approach, the adjacent faces of the gear-wheels being provided with jogs capable of engagement and disengagement by action of the cams, whereby a continuous rotation of the one 20 wheel will impart an intermittent rotation to the other, substantially as and for the purposes described.

In testimony whereof I have hereunto set my hand this 29th day of July, A. D. 1885.

JEROME F. BUSEY.
